UNITED STATES PATENT OFFICE.

HARRY DIXSON, OF PELLA, IOWA, ASSIGNOR TO ROLSCREEN COMPANY, OF PELLA, IOWA.

GUIDE CONSTRUCTION FOR SCREENS.

Application filed December 5, 1927. Serial No. 237,804.

The object of my invention is to provide a guide construction for rolling window screens wherein a flange on one edge of the guide is so arranged that when the guide is painted, the paint will not enter the interior of the guide, the parts being simple, durable and comparatively inexpensive.

More particularly it is my object to provide a guide for the edge of a screen upon which is arranged a pair of channel shaped flanges opening toward each other and between which the screen is adapted to travel and which channel shaped flanges receive any paint which may by capillary attraction enter into the interior of the guide when the outside thereof is being painted.

Still a further object is to provide the channel shaped flanged edges of the guides with one side or leg thereof being slightly longer than the other and thus coming closer to the corresponding side of the opposite portion of the guide so as to engage the screen traveling therebetween while the other or shorter leg of each channel shaped flange is spaced from the screen on each side thereof.

My invention is particularly adapted for use in connection with rolling window screens of the kind disclosed in my copending application filed May 13, 1925, Serial Number 29,960.

With these and other objects in view, my invention consists in the construction, arrangement and combination of the various parts of my guide construction for screens, whereby the objects contemplated are attained, as hereinafter more fully set forth, pointed out in my claims, and illustrated in the accompanying drawings, in which:—

Figure 1 is a plan view of a portion of the screen with my improved guide shown thereon.

Figure 2 is a sectional view taken on the line 2—2 of Figure 1, clearly disclosing the shape of the guide and particularly the channel shaped flanges.

Figure 3 is an enlarged sectional view through the track and screen together with a portion of a paint brush showing the position it assumes when the outside of the track is painted.

Figure 4 is a detail sectional perspective view of a portion of the guide construction.

In the accompanying drawings, I have used the reference character A to indicate

generally a guide construction which may be formed of a single blank of material bent substantially midway between its side edges as at 10 for forming a pair of abutting flanges 12 and 14.

The abutting flanges 12 and 14 as clearly shown in Figure 4 of the drawings, form the fastening flange of the guide construction. The sides or track fastening flange formed of the members 12 and 14, is formed with an elongated slot 16 through which a screw or the like 18 may be mounted wherein the guide construction is bodily capable of movement laterally.

The guide construction is used in connection with a rolling window screen 20 and a pair of guides are mounted upon a frame 22. The two guides used with each rolling window screen are mounted so that they open toward each other.

Each of the free edges of the flanges 12 and 14 are oppositely curved as at 24 for providing a tubular screen edge receiving guide 26. I have shown the tubular portion as formed substantially circular in outline although other shapes may be equally well used. The tubular portion 26 is formed with a slot 27 running lengthwise of the guide.

Upon each of the free edges of the portions 24 and adjacent the slot 27, I provide channel shaped flanges 28. The channel shaped flanges 28 open toward each other as clearly illustrated in Figures 2 and 4 of the drawings. The channel shaped flanges 28 are formed integral with the portions 24 and are connected thereto by a curved portion 30 which curved portion really forms one leg or side of each of the channel shaped flanges 28.

This side may be referred to by the reference numeral 32 and the other side, by the reference numeral 34.

The side 32 is somewhat longer than the side 34 and due to the fact that each of the flanges 28 open toward each other, causes the two curved portions 30 of the opposite flanges 28 to be positioned somewhat closer together than the edges of the sides 34.

The screen 20 is received between the two curved portions 30 and has its edge received within the tubular guide 26. The screen will be provided with enlarged portions 36 wherein it will be normally retained within the guide although, as a matter of fact, the

enlarged portions 36 may be pulled through between the two curved portions 30 of the guide construction, the curved edge or surface as at 38, allowing this to be done without mutilation of the screen or the guide construction.

The channel shaped flanges 28 which form the primary feature of my present invention, are so arranged that when the outside 10 of the guide construction is painted, the brush as at 40 may fit up against the guide and when the entire outside thereof is painted very little paint will enter into the guide proper.

15 It may be here mentioned, that paint entering upon the curved portion 30 or upon that portion which may coat with the screen, is detrimental to the easy and free operation of the screen up and down in the 20 guide construction.

The channel shaped flange 28 eliminates this possibility in the following manner. In the first place, the entire curved outer edge of the flange 28 may be painted in the manner as represented by the brush 40. Some little paint will by capillary attraction pass into the interior of the channel shaped flange or upon the edge of the leg 34.

25 The travel of the paint by capillary attraction is represented by the dotted lines 42. It will be noted that this leg 34 terminates short of the screen 20 so that even if paint does enter therebetween as represented by the reference numeral 42, it will not 35 come in contact with the screen or interfere therewith.

The channel shaped flange 28 provides a break between the portion 30 and the outer edge of the guide construction. It will be 40 readily seen that paint will not enter or travel into the guide construction proper and come in contact with the portion 30 when the outer sides of the guide receive an ordinary application of paint. Any paint 45 that may accumulate upon the interior of the guide construction will fill the channel shaped groove 44 which is formed by the channel shaped flange 28.

50 The accumulation of paint therein will cause no harm to the use of the screen.

It has been found with guide constructions where no paint receiving pocket was formed on the interior of the guide construction that at the time when the track was 55 painted, a certain amount of paint would enter the screen and within the track or guide and when the paint became dry it would stick and the screen would not operate freely.

60 My present guide construction including

the channel shaped flanges eliminates this undesirable feature and I have found in actual practice and use of my present track construction, that it does prevent paint from entering into the operating part of the guide 65 construction.

Some changes may be made in the construction and arrangement of the parts of my device without departing from the real spirit and purpose of my invention, and it 70 is my intention to cover by my claims, any modified forms of structure or use of mechanical equivalents, which may be reasonably included within their scope.

I claim as my invention:

1. A guide construction comprising a tubular guide portion, a fastening flange on one side of said guide portion, said guide portion having a slit opening therein running lengthwise thereof and a channel 80 shaped inwardly opening flange mounted on each edge of the slit opening.

2. A guide for the edge of a screen comprising a pair of similar members oppositely spaced for forming a tubular guide having 85 at one side flat fastening flanges and the other side having spaced projecting channel shaped flanges.

3. A guide having a longitudinal slot, the guide having adjacent to the slot, spaced 90 channel shaped members opening toward each other.

4. A guide construction comprising a tubular guide portion, a fastening flange on one side of said guide portion, said guide 95 portion having a slit opening therein running lengthwise thereof and a flange mounted on each edge of the slit opening, the last mentioned flanges being spaced for a portion of their widths a greater distance 100 than the width of said slit opening and having their inner surfaces facing each other.

5. A guide having a longitudinal slot, the guide having adjacent the slot spaced 105 flanges, each of which have portions projecting outwardly from the slot and having portions of their inner surfaces facing each other whereby the outer edges of the flanges protect the slot in the guide against paint 110 when the outer surfaces of the flanges are painted.

6. A guide having a longitudinal slot, the guide having adjacent to the slot, a channel shaped member opening inwardly whereby 115 said channel shaped member prevents paint from entering upon the edge of the slot as and for the purposes stated.

Des Moines, Iowa, November 25, 1927.
HARRY DIXSON.
